UNITED STATES PATENT OFFICE.

WILHELM PFANNKUCH, OF BERLIN, GERMANY, ASSIGNOR TO GENERAL ELECTRIC COMPANY, A CORPORATION OF NEW YORK.

CABLE SLEEVE.

Application filed December 18, 1922. Serial No. 607,584.

To all whom it may concern:

Be it known that I, WILHELM PFANNKUCH, a citizen of the Republic of Germany, residing at Berlin, Germany, have invented 5 certain new and useful Improvements in Cable Sleeves, of which the following is a specification.

The subject of the invention is a cable sleeve for high power lead sheathed cables, 10 which is provided with special means to effect a filling thereof with insulating substance free of air bubbles. The insulating mass, with which cable sleeves and cable joints for high power cables are filled, 15 should as fully as possible fill all hollow spaces within the sleeve and provide a thoroughly good insulation without any air spaces between the cable strands or their connecting means and the sleeve wall. The 20 presence of air chambers even if very small, between the strands and the inner walls of the sleeve is frequently the cause of perforations and explosive destruction of the sleeve, because the air enclosed in the insulating mass becomes ionized at the high volt- 25 ages employed.

In order to avoid the formation of hollow spaces or air chambers in the sleeve or in the cable joints, there have been tried many 30 widely different schemes, for example, filling masses have been used, which when cooling contract as little as possible and form minimum voids; the sleeve has also been filled in a vacuum in order to avoid the presence 35 of air.

In the present invention an entirely new course is taken in order to accomplish the said object and by means that may be used alone or in conjunction with the already 40 known means.

The new arrangement is based on the principle that the filling mass when it flows into the sleeve in a thick stream through a single opening at the highest part of the sleeve not only entrains air, but when striking the strands and connecting joints of the strands, especially in multiple cables, entraps the air present and prevents it from escaping.

In the present invention these disadvantages are eliminated by the following arrangements and instrumentalities:

The filling mass is not poured into the sleeve at the highest point, but through one or several lateral openings. Of especial advantage is the arrangement in which a

larger number of small openings are provided for the pouring in, which do not lie at the highest point of the sleeve.

In order to accomplish a safe pouring in of the mass through these lateral comparatively small openings, there is arranged on top of the middle part of the sleeve a dome-like extension serving as a collector receptacle, which in a manner forms a common distribution reservoir for the lateral openings. Within this dome, extending to both sides of the sleeve, there are advantageously provided openings in the highest point of the sleeve wall and as near as possible to the ends of the collector receptacle, which serve for the escape of the air from the sleeve.

The mode of application of the new arrangement will be understood by reference to the example shown in the drawing.

Figure 1 shows a cable sleeve partly in longitudinal section, partly in side view, and Fig. 2 is a cross section through the middle of the sleeve.

In the tubular lead sleeve shell 1 there are shown three strands 2 of insulated cable 3 spliced in any manner desired.

Over the top side of the tubular shell there is arranged in accordance with the invention, a dome-shaped auxiliary structure 4 or shell 4 which is provided with a filling in or pouring opening or nozzle 5 for the entrance of the filling mass. Within this dome 4 there are arranged at about $\frac{3}{4}$ of the height of the sleeve the filling-in openings 6, advantageously disposed therein in two or more rows in the longitudinal direction of the sleeve. Other openings 7 for the escape of the air are located at the highest point of the sleeve within the dome, as far as possible toward the two ends thereof.

Practically all lead sheathed cables are installed in a more or less horizontal position and accordingly it is customary to refer to the uppermost portion of such a cable or the joints thereof as the top, while the vertical or approximately vertical portions at the sides thereof are referred to as the sides and this terminology is employed in this case.

The mode of operation of the arrangement is as follows: The stream of the hot filling mass poured through the filling-in or pouring opening 5 spreads on the intermediate wall of sleeve 1 in the manner shown by the arrows in the drawing and enters

through openings 6, which together have a large opening area, into the sleeve, flows down along the walls on the inside and first collects at the bottom of the sleeve. The 5 mass gradually rises in the sleeve, presses the air out by the openings 7 and so gradually fills in all the intermediate spaces between the strands from below upwardly. As the air can freely escape upwardly without 10 hindrance by the entering mass, the enclosure or entrapment of air between the strands is avoided. In consequence of the arrangement of the air vents 7 on the uppermost portion of the sleeve all the air can 15 escape from the sleeve and be carried off by the dome 4 and the filling-in or pouring opening 5, and if need be also by a vacuum pump.

The arrangement of the large number of 20 filling-in openings 6 allows of a rapid distribution of the mass throughout the entire length of the sleeve. In consequence it is impossible, even when the mass in the sleeve 25 has cooled off somewhat, for spaces with air, or what is still more dangerous airless spaces to form.

By this arrangement in accordance with the invention, the further advantage is obtained that the mass does not strike the 30 strands in its hottest state, as is the case when directly poured in, but only after it has cooled off somewhat by extended contact with the sleeve walls. When the hot mass directly strikes the strands, as in the 35 methods hitherto used, there is danger that the impregnating mass of the paper or other material used for the insulation of the strands becomes liquid and escapes from the paper or other insulation into the filling 40 mass, whereby the insulation of the strands is decreased. This danger is eliminated in the practice of my invention.

A similar arrangement to that described 45 for cable sleeves, can also be employed in cable joints and other cable joints and other cable parts. While I have shown and de-

scribed the best embodiment of the invention known to me, I do not desire to be restricted thereto.

What I claim as new and desire to secure 50 by Letters Patent of the United States is:

1. A sleeve for sheathed electric cables comprising a tubular shell provided in its side walls with pouring holes, an auxiliary shell secured to the top portion of said 55 tubular shell to enclose said pouring holes and form with said tubular shell a distributing reservoir for filling material, and a pouring entrance in said auxiliary shell.

2. A sleeve for sheathed electric cables 60 comprising a tubular shell provided in its side walls with distributed pouring apertures and in its upper wall with vent apertures, an auxiliary shell secured to said tubular shell to enclose said side and vent openings and form with said tubular shell a distributing reservoir for filling material, and a pouring entrance in said auxiliary shell.

3. A sleeve for sheathed electric cables comprising a tubular shell provided with 65 two series of distributed pouring holes in its side walls and with vent holes in its upper wall towards the ends thereof, an auxiliary dome-shaped shell secured to the upper portion of said tubular shell to enclose both 70 series of distributed pouring holes and form with said tubular shell a distributing reservoir, and a pouring entrance in said auxiliary shell.

4. In combination, jointed sheathed cables, 80 a shell which surrounds the joint and also the adjacent ends of the cables, and is provided with pouring holes, located below the top thereof, a second shell which surrounds the first and is sealed at its ends, said shells 85 defining between them a reservoir for insulating material, and a pouring entrance in said second shell.

In witness whereof, I have hereunto set my hand this 29th day of November 1922.

WILHELM PFANNKUCH.
